his Attorney.

UNITED STATES PATENT OFFICE

2,363,723

MEANS FOR ROTATING MANDRELS

Stevenson Findlater, Pittsburgh, Pa., assignor to
 National Tube Company, a corporation of New
 Jersey

Application March 8, 1943, Serial No. 478,482

2 Claims. (Cl. 78—11)

This invention relates to mandrels for piercing billets and the like and, particularly to an improved means for rotating such mandrels.

In the steel industry, it is the general practice to force a mandrel through a billet or the like for piercing the same or to reduce the wall thickness of the billet or other workpiece. After the piercing operation and the mandrel has been moved to its retracted position and the pierced billet or workpiece has been stripped therefrom, it is customary to apply a cooling fluid and then a lubricant to the exterior surface of the mandrel before the same is inserted in another billet or workpiece for the next piercing or reducing operation.

Heretofore, it was difficult and practically impossible to obtain an even cooling effect of the mandrel and to lubricate evenly the surface thereof, in that, such mandrels were quite cumbersome and could not be easily rotated especially if the mandrels were long and had a relatively large diameter as is usually the case.

In the present invention, it is proposed to rotate such mandrels after each piercing or reducing operation in order that an even cooling effect of the mandrel will be obtained, and so that the lubricant can be evenly applied thereto. It is to an improved device or means for rotating the mandrel that the present invention relates.

Accordingly, it is the general object of the present invention to provide an improved means or device for rotating the mandrel after each piercing or reducing operation whereby an even cooling effect of the mandrel is obtained and, at the same time, an even coating of a lubricant can be quickly and conveniently applied to the surface thereof.

It is another object of this invention to provide an improved device or means for rotating a mandrel which is simple and inexpensive in its construction and, efficient and effective in its use.

Various other objects and advantages of this invention will be more apparent in the course of the following specification and will be particularly pointed out in the appended claims.

In the accompanying drawing there is shown, for the purpose of illustration, an embodiment which my invention may assume in practice.

In the drawing:

Figure 1 is a side elevational view of a conventional type vertical press showing the improved mandrel rotating device or means of my invention incorporated therewith;

Figure 2 is a sectional view taken on line II—II of Figure 1; and

Figure 3 is a sectional view taken on line III—III of Figure 1.

5 Referring more particularly to the drawing, there is shown a conventional type vertical press 2 for piercing heated billets and the like having a head 3 and a base or die holding member 4. There is disposed between the head 3 and the base 4, a pair of diametrically opposed rod-like members 5 upon which there is slidably mounted a yoke-like member 6. The yoke-like member 6 is connected preferably to the outer end of a piston rod or reciprocating member 7 which is 10 adapted to be actuated, preferably by means of a pneumatic cylinder (not shown). Beyond the yoke-like member 6 in the extreme lower or outer end of the piston rod 7, there is mounted a mandrel 8 for piercing the billet or workpiece which 15 is positioned in the base 4 in a manner well known to those skilled in the art.

According to the present invention, there is 20 arranged around the inner end of the mandrel 8 at the extreme end of the piston rod 7, a collar-like member 9 having a plurality of radially arranged lug-like portions 10 carried thereby and extending outwardly therefrom. The lug-like portions 10 are preferably four in number and arranged preferably 90 degrees from each 25 other similar in form to a star wheel. On the lower or outer side of the movable yoke-like member 6, there is mounted a bracket member 12 by means of machine screws 12^a in which there is mounted, preferably an hydraulic cylinder 13 having a piston rod 14 which is positioned 30 opposite the collar-like member 9 and which is arranged for movement in a plane substantially perpendicular to the axis of mandrel 8. On the outer end of the piston rod 14, there is positioned 35 a finger-like member 15 which is pivotally attached to the outer end of the piston rod 14 as at 16. There is also arranged on the outer end of the piston rod 14 directly opposite the finger-like member 15, a stop portion 17 with which 40 the finger-like member is adapted to cooperate. The finger-like member 15 is pivotally mounted at the upper end thereof so as to be disposed 45 normally in a vertical plane with the lower end extending to a point directly opposite the lug-like portions 10.

The improved mandrel rotating means or device of my invention functions in the following manner. After the billet or workpiece has been pierced by the downward movement of the mandrel 8 and the mandrel has been withdrawn to 50

its retracted position, as shown in Figure 1 of the drawing, a suitable pressure fluid is introduced into the cylinder 13 and the piston rod 14 thereof is caused to move outwardly therefrom or to the left as shown in the broken lines of Figure 1. In such movement, the finger-like portion 15 carried thereby strikes one of the lug-like portions 10 arranged in its path with the mandrel 8 and will rotate the same through an arc of substantially 90 degrees. After the mandrel has been rotated, a pressure fluid is introduced into the opposite end of the cylinder 13 so that the piston rod 14 is moved to its retracted position or to the right as shown in the full lines of Figure 1. It will be seen that the next succeeding lug-like portion 10 will be moved directly in the path of travel of the finger-like portion 15 after the same has moved a substantial distance past the center of the mandrel and will tend to prevent retractable movement of piston rod 14 together with the finger-like portion 15 carried thereby. However, when the finger-like portion 15 strikes this next succeeding lug-like portion 10, it will pivot about its pivotal connection at 16 and ride over the top of this lug-like portion. After the piston rod 14 has moved far enough, it will be seen that the finger-like member 15 will drop clear of this next lug-like portion and fall due to gravity against the stop portion 17 and in position for the next rotative operation of the mandrel. By rotating the mandrel by means of my improved device, it will be seen that the mandrel may be evenly cooled and that a lubricant can be evenly applied to the exterior surface thereof either while the same is being rotated or after each quarter turn thereof.

It will be understood that my improved mandrel turning or rotating device can be conveniently incorporated with a draw bench wherein the mandrel is horizontally disposed as well as a vertically disposed mandrel as shown in the drawing. In such a draw bench, the blank or billet while disposed on the mandrel usually is forced through a series of annular dies so as to reduce the wall thickness of the blank or work-piece in a well known manner.

While I have shown and described one specific embodiment of my invention, it will be understood that this embodiment is merely for the pur-

pose of illustration and description and that various other forms may be devised within the scope of my invention, as defined in the appended claims.

5 I claim:

1. In combination with a mandrel for piercing billets and the like, means for rotating the mandrel after each piercing operation comprising four radially extending lug-like portions arranged with and projecting outwardly from the periphery of the mandrel with the lug-like portions being spaced substantially 90 degrees from each other, an hydraulic cylinder mounted for operative movement in a plane substantially perpendicular to the axis of said mandrel, and a finger-like member pivotally mounted on the outer end of the piston rod of said cylinder which is adapted to cooperate with said lug-like portions, said finger-like member constructed and arranged so as to strike said lug-like portions carried by said mandrel successively so as to rotate the same.
2. In combination with a mandrel for piercing billets and the like, means for rotating the mandrel after each piercing operation comprising four radially extending lug-like portions arranged with and projecting outwardly from the periphery of the mandrel with the lug-like portions being spaced substantially 90 degrees from each other, means mounted for reciprocable movement in a plane substantially perpendicular to the axis of said mandrel, and means carried by said reciprocable means which is adapted to cooperate with said lug-like portions carried by said mandrel so as to rotate the same, said last mentioned means being mounted for movement relative to said reciprocable means and adapted to positively contact said lug-like portions carried by said mandrel so as to rotate the same through an arc of substantially 90 degrees when the reciprocable means is moved in one direction and when the same is moved in the opposite direction adapted to yieldably contact the next succeeding lug-like portion which is disposed in the path of travel of said reciprocable means after the mandrel has been rotated thereby through substantially 90 degrees so as to permit the reciprocable means to return to its normal position without effecting rotative movement of said mandrel.

STEVENSON FINDLATER.
